UNITED STATES PATENT OFFICE.

GEORGE W. D'ARCY, OF BOSTON, MASSACHUSETTS.

NOZZLE FOR HUMIDIFYING APPARATUS.

Application filed January 7, 1920. Serial No. 350,031.

To all whom it may concern:

Be it known that I, GEORGE W. D'ARCY, a citizen of the United States, and a resident of Boston, in the county of Suffolk 5 and Commonwealth of Massachusetts, have invented an Improvement in Nozzles for Humidifying Apparatus, of which the following description, in connection with the accompanying drawings, is a specification, 10 like characters on the drawings representing like parts.

This invention is an improvement in nozzles of the tube-orifice type shown and described in my Patent No. 1,302,515, dated 15 May 6, 1919, for method and apparatus for humidifying air.

The object of the invention is to provide a dripless nozzle of simple construction that can be used with systems employing either 20 compressed air or steam as the diffusing medium, and that will give a wider distribution of vapor laterally so as to increase the area of diffusion from the nozzle.

One feature of the invention consists in 25 thinning the walls of the tube at the orifice; a second feature in making a recess in the inner wall of the tube surrounding the orifice; and also in making the tube in two concentrically arranged parts, one of which 30 has a hole or recess already referred to and the other a thinned portion consisting of the sleeve only disposed opposite the hole and through which the orifice is cut.

In order that the construction and operation of the invention may be understood, I 35 have illustrated it in the accompanying drawing in a preferred form that experience has shown to be well adapted to the usual conditions of use in mill buildings.

40 In the drawings, Fig. 1 is a side view of a nozzle in the position in which it is intended to be used;

Fig. 2 is a vertical-section of the same on the line 2—2 in Fig. 1; and

45 Fig. 3 is a view similar to Fig. 1 with the outer sleeve removed.

The nozzle shown in the drawings consists of two parts, a straight pipe 11 which is adapted to be connected at its upper end to 50 the supply pipe by a socket 12, and an apertured sleeve 13 which is slipped on over the lower end of the pipe 11 and secured by brazing, soldering, or other suitable means.

The pipe 11 has two oppositely disposed 55 curvilinear orifices or holes 14 in its side walls at a short distance from its lower end;

and the sleeve 13 has two elongated apertures 15 through its side walls near its upper end, the orifices being located opposite the holes 14 in the pipe in the assembled nozzle. 60 The portion of the sleeve containing the orifices has a lip or flange 16 surrounding the sleeve immediately below the lower edges of the orifices. The lower ends of the pipe and sleeve are closed by a screw cap 17. 65

The orifices 15 need not be restricted to two in number, and need not be diametrically opposed; but it is found that two or more comparatively narrow orifices in a thin walled tube are more effective and give 70 a more uniform distribution of vapor over a large area than wider orifices in a tube having thicker walls.

The portion of the sleeve edge overlying the edge of the orifice 14 provides a baffle 75 plate, as it were, against the inner side of which part of the circular stream of mingled air and water is projected as it leaves the orifice 14.

The result is that the overlying edge 80 about the elongated aperture 15 acting as a baffle plate retards the flow of air and water somewhat causing a further and more complete comingling thereof, with the result that a finer and very much more completely 85 mixed or diffused stream of vapor is projected into the room with very much improved and more widely extended results. With this construction I am able to humidify to a satisfactory degree a very much 90 greater number of cubic feet of air than can be done by any other construction of which I have knowledge. A curvilinear hole or recess will not do it and a rectangular aperture alone will not do it; but the combination of the two with the one overlying the other does produce the result above described. This device is far and away more efficient than any other form of nozzle 95 known to me.

100 It may be possible to vary the construction of the present embodiment of my invention without departing from the spirit of the invention or the scope of the claims.

I claim the following as my invention:

1. A nozzle for humidifying apparatus comprising a tube having a closed lower end and a curvilinear orifice in its side wall above the end, a sleeve about the tube, an aperture in the sleeve of less width than the 110 corresponding dimension of the aperture in the tube, whereby the overlying edge of the

aperture in the sleeve acts as a baffle plate to disturb the co-mingled stream of air and water as it leaves the orifice.

2. A nozzle for humidifying apparatus comprising a tube having a closed lower end and an orifice in its side wall above its end, and a sleeve about the tube, an aperture in the sleeve smaller than and registering with the orifice in the tube, the overlying edge of 10 the aperture acting to baffle the stream of air and water to dissipate the same and more thoroughly diffuse the vapor throughout the space adjacent the nozzle.

3. A nozzle for humidifying apparatus comprising a tubular member having a

curvilinear opening in its side wall, a sleeve over the tube with a circumferential slit therein registering with said opening and of less width than the corresponding dimension of the opening whereby the overlying edge of the slit acts as a baffle plate against which the stream of air and water is projected from the curvilinear opening with resulting more thorough diffusion of the vapor throughout the space adjacent the nozzle. 20 25

In testimony whereof, I have signed my name to this specification.

GEORGE W. D'ARCY.
